Besser and Hardwig
ATTORNEYS.

UNITED STATES PATENT OFFICE.

HARRY M. ROSE, OF PHILADELPHIA, PENNSYLVANIA, ASSIGNOR TO THE ROSE COMPANY, OF PHILADELPHIA, PENNSYLVANIA, A CORPORATION OF PENNSYLVANIA.

EASEL.

Application filed May 31, 1928. Serial No. 281,972.

The object of my invention is to provide an easel which is adapted when in use to assume a position inclined to the vertical and the angle of inclination of which may be varied 5 within wide limits. A further object of the invention is to adapt such easel to the holding of articles of widely different shapes, such as angular or circular flat cards, pins, flags, flowers, etc. A further object of the invention 10 is to provide an easel of pleasing contour, which contour, however, is not fully displayed until the supporting tab of the easel is bent into supporting position.

In the drawings, which show a preferred 15 embodiment of the invention—

Fig. 1 is a plan of the blank cut and scored as required to form an easel.

Fig. 2 is a plan view of the easel, shown as if standing on the plane of the paper.

20 Fig. 3 is a front view of the standing easel of Fig. 2, with an article mounted on it.

Fig. 4 is a side view of the showing of Fig. 3.

The blank from which the easel is formed 25 comprises an approximately rectangular body *a* having a segmental or arch-shaped top *b*. The body *a* is provided with a slit *c* extending obliquely upward from the bottom edge near one end and thence extending 30 parallel to the bottom edge, the ends of the horizontal part of the slit being equidistant from the respectively adjacent upright edges of the body. The body is scored or otherwise indented along a line *d* extending from the 35 bottom edge near the other end upward obliquely to the closed end of the horizontal portion of slit *c*. Thereby a tab *e* is formed which is adapted to be bent back into position to support the easel.

40 In the top *b* is formed a slit *f* extending parallel to the convexly curved upper edge of said top.

If the tab *e* is bent back so as to extend at a 45 relatively small angle to the easel body, it will support the easel in a position slightly inclined to the vertical. The further the tab *e* is bent back, the greater the inclination to the vertical that the easel will assume.

When the tab *e* is bent back, the easel will present a greatly improved appearance, since 50 it will comprise a body resting on end legs, with the central part of the body spaced from the support on which the easel rests.

A slit of the shape shown at *f* is adapted to receive and support various articles, such as 55 flat articles of any shape, of which card *g* is shown as an example, or flower stems, pins carrying flags, place cards, etc. The easel itself is adapted to function as a place card if desired.

Having now fully described my invention, what I claim and desire to protect by Letters Patent is:

1. An easel comprising a body provided 65 with a slit extending obliquely upward from the bottom edge near one end and thence parallel to the bottom edge toward the other end and scored along an oblique line extending obliquely upward from the bottom edge near the last named end to the closed end of said slit, the top edge of the easel being convexly curved and provided with a slit extending substantially parallel to said curved top edge.

2. An easel comprising a body provided 75 with a slit extending obliquely upward from the bottom edge near one end and thence parallel to the bottom edge toward the other end and scored along an oblique line extending obliquely upward from the bottom edge near the last named end to the closed end of said slit, the top edge of the easel being convexly curved from a point midway between opposite ends of the easel to points near said opposite ends and thence extending straight and at right angles to said ends, the easel being provided with a curved slit spaced from and extending substantially parallel to said curved top edge and above the level of the straight parts of said top edge.

In testimony of which invention, I have 90 hereunto set my hand, at Philadelphia, Pennsylvania, on this 21st day of May, 1928.

HARRY M. ROSE.
